Patented Nov. 15, 1921.

WITNESS:

Wm. D. Bell.

INVENTOR,

Michelangelo Ferraro,
BY
John W. Stewart.
ATTORNEY

UNITED STATES PATENT OFFICE.

MICHELANGELO FERRARO, OF PATERSON, NEW JERSEY.

HAMMER.

1,396,822.

Specification of Letters Patent. Patented Nov. 15, 1921.

Application filed December 31, 1920. Serial No. 434,293.

To all whom it may concern:

Be it known that I, MICHELANGELO FERRARO, a citizen of the United States, residing at Paterson, in the county of Passaic and State of New Jersey, have invented certain new and useful Improvements in Hammers, of which the following is a specification.

The object of this invention is to provide a hammer, hatchet or other striking implement with a clip which will prevent its head from coming off and to construct said clip so that it will be simple and inexpensive to manufacture and readily attachable to and detachable from the implement and so that it will protect against injury the end of the wooden handle of the implement where it penetrates the head and is thereby exposed.

In the drawing.

20 Figure 1 is a side view, partly in section, of a hammer embodying my invention;

Fig. 2 is a head-end view of the implement;

Fig. 3 is a section on line 3—3, Fig. 1;

25 Fig. 4 is an enlarged fragmentary view of the handle and head and the cap, the latter being detached; and

Fig. 5 shows a modified form of the cap.

The wooden handle *a* of the implement is 30 fitted into the socket *b* of the head *c* of the implement in the usual way, the head being prevented from movement inward on the handle in any way, as by a shoulder *d* formed on the latter.

35 The stub *e* of the handle over which the head is fitted protrudes outwardly somewhat beyond the handle, as illustrated best in Figs. 3 and 4; this is not indispensable, but it is desirable in order to avoid recessing 40 the outer face of the head *c* in order to receive my means to protect the head from coming off the handle. The protruding end of the stub *e* has grooves *f* formed opposite each other and transversely of and in the 45 side or broader faces of said stub; these grooves afford shoulders *g* facing the head *c* and against which my aforesaid means is to obtain abutment. The cap forming my aforesaid means in Figs. 1 to 4 is formed of

50 an oblong piece *h* of stiff sheet metal having integral rectangular wings *i* at its four sides and each of the same length as the corresponding side, said wings being bent up into perpendicular relation to the piece *h* so that 55 an oblong box-like structure results closed at all sides excepting the side opposite the

piece *h*. The two long sides have rebent folds *j* formed therein, the same extending inwardly and forming inwardly projecting flanges substantially parallel with the piece 60 or wall *h*; the outer edges of these sides preferably extend somewhat beyond the sides of the box-like structure or cap, as indicated at *k*. The two short sides *i* have their outer portions bent outwardly, as indicated at *l*, and lying in the same plane as the edge portions *k* of the long sides. (Compare Figs. 3 and 4). When the cap is first formed it will preferably have one short side *i* left extended, or in the same plane 70 as the wall *h* (Fig. 4).

Having assembled the head and handle, which will bring the rear side of the grooves *f* flush with the outer face of the head *c*, the cap is applied to the stub *e* by sliding 75 it thereon transversely thereof and in such manner that its flanges *j* enter the grooves *f* of the stub, upon which the side *i* of the cap left extended as in Fig. 4 is bent into perpendicular relation to the wall *h* as shown 80 in Figs. 1 and 2.

It will be well to form extensions or ears *m* on the ends of two opposite sides *i* which can be bent so as to overlap the other two sides and thus give strength and rigidity to 85 the cap; in Fig. 5 these ears *m* are formed on the longer sides *i* but in Figs 1 to 4 they are formed on the shorter sides, the latter being the preferable construction because the ears will then reinforce the longer sides 90 against spreading and the flanges *j* consequently against working out of the grooves *f*.

It will be seen that the clip extends over the outer end of the handle and thus affords protection thereto, besides being an inexpensive, simple and readily attached and detached means for preventing the head from 95 coming off.

Having thus fully described my invention, what I claim as new and desire to secure by 100 Letters Patent is:—

1. In combination, with the members to be interlocked and one of which penetrates and protrudes from the other and has on its protruding portion a shoulder facing 105 toward the other member, a sheet-metal clip capping the protruding end of the first member and forming an abutment limiting the displacement of said other member toward said end and having an inward rebent 110 fold bearing against said shoulder.

2. In combination, with the members to

be interlocked and one of which penetrates and protrudes from the other and has on its protruding portion a shoulder facing toward the other member, a sheet-metal clip 5 capping the protruding end of the first member and forming an abutment limiting the displacement of said other member toward said end and having four rectangularly

arranged side walls, one of said side walls having an inbent portion bearing against said shoulder and each side wall next adjoining the first-named side wall having ears outwardly overlapping the latter wall and the side wall opposed thereto. 10

In testimony whereof I affix my signature.
MICHELANGELO FERRARO.
